UNITED STATES PATENT OFFICE.

CHARLES R. KLINE, OF READING, PENNSYLVANIA.

COMBINATION BOILER.

Application filed September 9, 1920. Serial No. 409,079.

To all whom it may concern:

Be it known that I, CHARLES R. KLINE, a citizen of the United States, residing at Reading, in the county of Berks and State 5 of Pennsylvania, have invented certain new and useful Improvements in Combination Boilers, of which the following is a specification.

My invention relates more particularly to 10 boilers adapted for heating residences or like purposes, my main object being to provide for the convenient and economical use of such boilers in accord with the greatly varying needs incident to variations in 15 weather and other conditions.

The invention consists essentially in combining with an ordinary fire-grate boiler, a 20 separately formed built-in section provided with a fluid-fuel burner and conduits and forming a separate combustion chamber arranged in communication with the same passage-ways through which the solid-fuel products of combustion are discharged; so 25 that said fluid-fuel section may be readily and effectively employed either alone to produce the relatively small amount of heat required for distribution in moderately cold or damp weather, or to supplement the solid-fuel heat production when called for; as 30 fully described in connection with the accompanying drawings and specifically pointed out in the claims.

The drawing illustrates the application of 35 my invention to a known type of boiler, in a simple manner adapted to make clear the essential features of the invention; Fig. 1 showing a sectional view of my fluid-fuel section in connection with the adjacent parts of a sectional boiler and with a partial front 40 view of the latter; and Fig. 2 showing a sectional view on the line 2-2 of Fig. 1.

The known type of boiler indicated is 45 made up of a series of connected water-containing sections 5, 5, 5, forming in combination with an ash-pit base portion provided with door fronts 7 and 8, a suitable solid-fuel combustion chamber, with communicating passage-ways, as 9 and 10, through the connected water-containing sections for dis- 50 charging the products of combustion. As specifically indicated, these sections form a so-called side-feed boiler having a relatively wide fuel and combustion chamber with two solid-fuel firing doors 11 and ash-pit doors 55 12; and my separately operative fluid-fuel section 20 is shown as located midway be-

tween these two firing doors, and arranged in communication with the sections 5, 5, on each side thereof.

My special section 20, as shown, is made 60 to correspond in general form with the co-operating ordinary water-containing sections 5, but provides in itself a combustion chamber 21 separated from the adjacent solid-fuel combustion chambers by spaced-apart water walls 22; said chamber 21 being 65 in communication above with the passage-way 9, through which the products of combustion from chamber 21 are also discharged into the chimney-connected passage-way 10, 70 and the water-containing space being in communication with that of the sections 5 as usual. The section 20 is carried upon integrally formed wall or partition plates 24, 24, as indicated, which form a separate 75 chamber 25 on the level of the adjacent ash-pit chambers 27, and below the water-wall bottom 26 of the combustion chamber 21. Through the front wall 28 of this lower chamber 25, which may be provided with 80 a doored aperture 34, extends a conduit 30 for the fluid-fuel, liquid or gass, to be used in the combustion chamber 21; which conduit passes through the bottom 26 and is connected to a suitable burner 31 in the 85 chamber 21; air passages 32 to the latter being also provided as indicated. A suitable opening 33 is provided for access to the chamber 21, through the front wall thereof, to which a door may be insulatingly applied 90 as shown in my Patent No. 1,319,096 issued Oct. 21, 1919.

In operating my improved boiler all the 95 products of combustion, whether from solid or fluid fuel employed, pass through the sec- 100 tion passage-ways 9 and 10, to the chimney; but either the solid fuel or the fluid fuel may be used independently, or both may be used together, as weather or other conditions may make desirable; the fluid fuel be- 105 ing very conveniently, satisfactorily, and economically employed alone during the early and late months of the cold season or occasional damp weather, and serving to readily supplement the usual solid-fuel heat production in extreme weather. The applica- 110 tion of the invention involves comparatively inexpensive changes in constructions heretofore employed, and the showing specifically set forth may be readily modified to suit desired patterns and arrangements.

It will be understood that the coal heated

water holding sections 5 are connected to each other by the nipples 35, and that the gas heated water holding section 21 is connected to the contiguous coal heated sections 5 by the nipples 36, so that a free and unimpeded water circulation is permitted, the inlet and outlets for the sectional boiler being of the usual character and requiring no further description. The back flue 10 of the gas heated section 20 may be connected with the flues 9 in any suitable manner as by the flue 37, said flue 10 having a connection or exit to a chimney (not shown) as hereinbefore referred to.

15 What I claim is:

1. In a device of the character stated, a plurality of water holding sections, provided with transverse flues and communicating water passages, and a grate for the reception of solid fuel, in combination with a water holding section adapted to be heated by gas, said latter section having a water connection to said other sections, and a flue in communication with said transverse flues, a gas burner located in the lower portion of said gas heated section, upright water jacketed walls in said gas heated section located on each side of said gas burner, and a support for said gas burner having vertically

extending air inlet passages leading from a chamber below said gas burner to the combustion chamber above the latter.

2. In a device of the character stated, a plurality of upright water holding sections provided at their lower portions with grates 35 for solid fuel and at their upper portions with transverse flues and water connections, in combination with an upright water holding section adapted to be heated by a gas burner, said latter section having a water connection to the other sections and an outlet flue in communication with said transverse flues, upright bottom walls upon which said gas heated section is supported forming a lower chamber, upright water jacketed walls 45 for said gas heated section supported upon said bottom walls and having a combustion chamber formed therebetween, a gas burner positioned in the lower portion of said combustion chamber between said water jacketed walls, and ports in proximity to said gas burner leading from said bottom chamber to said combustion chamber for conveying air into the latter from said bottom chamber.

55 In testimony whereof I affix my signature.

CHARLES R. KLINE.
